UNITED STATES PATENT OFFICE.

RALPH H. SLEICHER, OF TROY, NEW YORK.

AMBULANCE.

1,150,710.

Specification of Letters Patent. Patented Aug. 17, 1915.

Application filed April 16, 1914. Serial No. 832,322.

To all whom it may concern:

Be it known that I, RALPH H. SLEICHER, a citizen of the United States, residing at Troy, in the county of Rensselaer and State 5 of New York, have invented certain new and useful Improvements in Ambulances, of which the following is a specification, reference being had therein to the accompanying drawing.

- 10 The present invention relates to improvements in ambulances, for transporting invalids, one object of the invention, being the provision of an ambulance especially designed for use in connection with the hospital apparatus, as set forth in my co-pending application filed January 9, 1914, Serial No. 811,163, and in connection with the bed structure shown in my co-pending application filed even date herewith, one object of 15 the invention being the provision of a longitudinal guide-way upon or adjacent the floor of the ambulance, by means of which a couch member carried upon casters may be readily placed into or removed from the 20 ambulance and by means of which the couch member will be held against transverse movement within the ambulance, and may be locked against longitudinal movement during the transportation.
- 25 A further object of the present invention, is the provision of an ambulance having longitudinal guide-ways for casters, with means carried thereby for engaging a couch member provided with casters to lock the couch member against longitudinal movement after 30 the same has been properly positioned in place to thus insure the rigid fastening of the couch during the movement of the ambulance.
- 35 With the foregoing and other objects in view which will appear as the description proceeds, the invention resides in the combination and arrangement of parts and in the details of construction hereinafter described 40 and claimed, it being understood that changes in the precise embodiment of the invention herein disclosed can be made within the scope of what is claimed without departing from the spirit of the invention.
- 45 In the drawings—Figure 1 is a longitudinal sectional view through the ambulance body showing the couch member in position thereupon when the ambulance is in motion.

Fig. 2 is a top plan view showing the floor plan of the ambulance without the couch member. Fig. 3 is a cross section through the floor of the ambulance adjacent the rear thereof. Fig. 4 is a detail view of the couch holding device or fastener.

Referring to the drawings, the numeral 1 designates the floor of the ambulance, which has attached thereto in any desired manner, the two guide-ways 3 which are preferably recessed at 4 for the slidable reception longitudinally of the ambulance of the casters 5 carried by the couch member 6. By this means it will be seen that the couch member may be moved longitudinally of the ambulance, and that by reason of the engagement of the casters with the guide-ways, the 65 same will be held against transverse movement.

In order to provide a means for locking the couch member against longitudinal movement during the movement of the ambulance, the pivoted clamping members 5 are employed, and are connected to the guide-ways at the rear end so as to engage the longitudinal member 6 of the couch member, and thus clamp the same downwardly upon 70 the ways. By this means, the couch member may be readily and quickly released so that the same may be removed, thus facilitating the handling of the patient, the present couch member being constructed for co-operative with the ether-carriage set forth in my application Serial No. 811,163, and the said structure shown in my co-pending application filed even date herewith.

What is claimed is:

1. An ambulance, having a body, a pair of parallel guide-ways mounted upon the bottom thereof longitudinally of the ambulance, a couch member having two parallel longitudinal tubes and being adapted to be 95 supported upon the guide-ways and having a plurality of means engageable with said ways to permit longitudinal movement of the couch member and to prevent transverse movement, and pivoted clamping means attached to the guide-ways for engaging the tubes of the couch member to lock the couch member downwardly upon the ways against longitudinal movement.

2. An ambulance, including a body, a pair 105 of open ended caster receiving parallel

guide-ways attached to the bottom of the body and accessible through the rear end thereof, and two outwardly swinging locking members pivoted to the outer portions 5 near the rear ends of said guide-ways and forming means for locking a couch member downwardly upon the guide-ways.

In testimony whereof I affix my signature in presence of two witnesses.

RALPH H. SLEICHER.

Witnesses:

ROBERT A. STEVENS,
J. F. WHELAN.
